US00D427564S

United States Patent [19]

Wu

[11] Patent Number: Des. 427,564

[45] Date of Patent: ** Jul. 4, 2000

[54] **BATTERY CHARGER FOR MOBILE PHONE BATTERY AND MOBILE PHONE**

[75] Inventor: **Michael Wu**, Hsin Tien, Taiwan

[73] Assignee: **Formosa Electronic Industries Inc.**, Taiwan

[**] Term: **14 Years**

[21] Appl. No.: **29/108,059**

[22] Filed: **Jul. 21, 1999**

[51] LOC (7) Cl. **13-02**

[52] U.S. Cl. **D13/107**; D13/108

[58] Field of Search D13/107, 108; D14/251, 253; 320/110-115
